US00D830981S

(12) **United States Design Patent** (10) Patent No.: **US D830,981 S**
(45) Date of Patent: **** Oct. 16, 2018**

(54) **SUSCEPTOR FOR SEMICONDUCTOR
SUBSTRATE PROCESSING APPARATUS**

(71) Applicant: **ASM IP Holding B.V.**, Almere (NL)

(72) Inventors: **Sang Jin Jeong**, Chungcheongnam-do (KR); **Jeung Hoon Han**, Gyeonggi-do (KR); **Young Seok Choi**, Daejeon (KR); **Ju Hyuk Park**, Chungcheongnam-do (KR)

(73) Assignee: **ASM IP Holding B.V.**, Almere (NL)

(**) Term: **15 Years**

(21) Appl. No.: **29/604,288**

(22) Filed: **May 16, 2017**

(30) **Foreign Application Priority Data**

(57) **CLAIM**

The ornamental design for a susceptor for semiconductor substrate processing apparatus, as shown and described.

DESCRIPTION

FIG. 1 is a perspective view of a susceptor for semiconductor substrate processing apparatus, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is a sectional view taken along line 9-9 of FIG. 6.
